UNITED STATES PATENT OFFICE.

REMI J. HENRY, JR., OF JERSEY CITY, NEW JERSEY, AND WILLIAM J. KASSLER, OF BROOKLYN, NEW YORK.

AUTOMATIC SHUT-OFF FOR GAS-BURNERS.

SPECIFICATION forming part of Letters Patent No. 400,839, dated March 26, 1889.

Application filed July 28, 1887. Serial No. 245,563. (No model.)

To all whom it may concern:

Be it known that we, REMI J. HENRY, Jr., of Jersey City, in the county of Hudson and State of New Jersey, and WILLIAM J. KASSLER, of Brooklyn, in the county of Kings and State of New York, have invented a new and useful Automatic Shut-Off for Gas-Burners, of which the following is a specification.

Our invention relates to a device for automatically shutting off the flow of gas to gas-burners; and the object of our invention is to prevent the escape of gas from the burner when by accident, ignorance, or design the gas is extinguished without closing the stop-cock, or the stop-cock is accidentally or intentionally opened after the extinguishment of the gas.

In the accompanying drawings, Figure 1 represents a gas-burner and our automatic shut-off applied thereto; Fig. 2, a vertical section of the same, the section being taken on line *xx* of Fig. 1 and the figure much enlarged; Fig. 3, a similar view taken on line *yy* of Fig. 2; Fig. 4, a horizontal section taken on line *zz* of Fig. 3. Fig. 5 represents in section another construction of the device.

Referring to the drawings, B represents a gas-burner, and F a fixture having a stop-cock, C, for turning the gas on and off in the usual manner.

In the base of the burner is a cylindrical valve-seat, 1, which is formed by drilling a hole transversely into the burner from one side across the gas-passage *p*. In the said seat is placed a cylindrical valve, 2, one end of which projects out of the seat and is fitted with an arm, *a*. The valve is provided with an opening, 3, in line with the gas-passage *p*. Preferably this opening is of a rectangular form.

The valve 2 is automatically opened and closed by the expansion and contraction of a plate, 4, that connects with the valve, and is placed in a position where it is affected by the heat from the flame of the burner. The said plate is by preference composed of two metals of unequal expansibility at the same temperature, so that when exposed to heat the plate will be caused to curve and the free end thereby moved in a certain direction. To gain these objects the plate is composed of a lamina of brass and one of steel soldered together;

but other metals may be substituted for those mentioned, and a plate of one metal only may be used; but the compound plate is preferred. The plate is curved and shaped in such a manner as to connect by one end with a fixed object and by the opposite end with a bar which is in pivotal connection with the shut-off valve, while the intermediate portion is in proximity to the flame of the burner. One end is thus left free to move, while the other is immovable. The preferred form of the plate 4 is that of an inverted **U**, and it is applied to the burner so that the metal which expands the most forms the exterior surface of the plate; but in practice the adjustment of the plate with reference to the position of the metals of which it is composed will depend upon the direction the valve is arranged to move to open the passage to the burner.

The **U**-shaped plate is placed over the burner-top *t*, its arched portion being close to and parallel to the plane of the flame, with which it is preferred the plate shall not be in contact. The plate is held in position by fastening the end *f* of one leg to one side of the burner or other fixed object, and the opposite end, *f'*, by a joint, 5, connected with rod *R*, which has its end pivoted to the valve-arm *a*. The shut-off valve 2 is held closed by the spring-plate 4, as shown in Fig. 1, that being its normal position. Therefore when the cock is opened the said valve prevents the passage of the gas to the burner-tip; hence there can be no escape of gas after merely opening the cock, but only by opening the shut-off valve, and either holding it open positively or by expanding the plate 4 by means of heat. The valve being positively and permanently connected with the plate 4, it cannot be opened or shut without a movement of the said plate; nor can the latter be moved in the direction it is caused to move by heat without moving at the same time the valve.

As indicated in Fig. 1, the full lines represent the position of the shut-off valve and the plate 4 when the gas is not burning, and the broken lines when the gas is burning. To light the gas, the stop-cock *C* is opened to its fullest extent, thereby admitting the gas to the burner under the valve 2, which remains closed. On applying a light to the tip of the

burner the heat therefrom causes the plate 4 to expand and partly open the valve 2, whereupon the gas flows through the valve-opening to the burner-tip and is lighted by the flame applied to the plate. The gas-flame now supplies heat, by which the plate is further expanded and the shut-off valve opened to its fullest extent. As long as the gas remains burning the valve is held open; but when it is extinguished the plate C immediately contracts and closes the valve.

The utilization of the above-described device to shut off the flow of gas automatically after the flame has been extinguished without closing the stop-cock may be readily understood from the foregoing. If the gas be blown out, for example, the contraction of plate 4 immediately closes valve 2 and shuts off the gas before any injury can result. So, too, if the stop-cock be closed and immediately reopened, accidental or intentional suffocation by gas escaping from burners may by the use of this device be entirely prevented.

In the modification Fig. 5 the U-shaped plate has both legs of equal length, and the rod R, which is made in two parts, connects with the plate at 6, and the joint is formed between the two parts of the rod R. The expansion-plate, rod, and valve are also inclosed by a cylindrical casing, 7, which connects with the base of the burner below the valve. An opening is made in the side of the case, through which a projection from the rod R extends, and terminates with a knob, k. When it is desired to light the gas in a great hurry, the valve can be opened by pushing on the end of

the rod R, or in the incased burner, Fig. 5, in the end of the projection, or the knob k.

We claim—

1. In an automatic shut-off for gas-burners, 40 the combination, with a gas pipe and burner, of a valve held in a suitable seat in the burner, and provided with an arm or stem, and a U-shaped expansion spring-plate placed over the burner-tip, having one end fixed and the 45 other positively connected with the valve-stem, and freely movable therewith at all times to open and close the valve, the construction being such that the valve is kept closed by the spring-plate, whatever the 50 condition of the cock, unless the gas is lighted, substantially as specified.

2. The combination, with the gas pipe and burner, of a valve provided with an arm and held in a suitable seat in the burner, a U- 55 shaped expansion - plate placed over the burner-tip and having one end fixed and the other movable, but positively and permanently connected with the arm of the valve, the cylindrical casing 7, inclosing said valve-arm 60 and expansion-plate, and a rod, R, provided with a projection that extends outside of said case through a suitable opening therein, substantially as specified.

In testimony that we claim the foregoing 65 as our invention we have hereunto subscribed our names this 19th day of September, 1888.

REMI J. HENRY, JR.
W. J. KASSLER.

In presence of—

WILTON C. DONN,
HARRY N. HOLDEN.
